UNITED STATES PATENT OFFICE.

JOHN PELL NORTHEY, OF TORONTO, ONTARIO, CANADA.

KEY BOLT.

Application filed December 17, 1921. Serial No. 523,189.

To all whom it may concern:

Be it known that I, JOHN P. NORTHEY, of the city of Toronto, in the county of York, Province of Ontario, Canada, a subject of the King of Great Britain, have invented certain new and useful Improvements in Key Bolts, of which the following is a specification.

This invention relates to bolts which are slotted so that a taper key may be employed to set up the bolt instead of a nut. Ordinarily in such bolts the slot extends close to the end of the bolt and the back of the taper key directly engages the end of the slot. Under such conditions it is difficult to drive the key tight without deforming the bolt owing to the transverse frictional pressure exerted by the key against the outer end of the bolt, which necessarily extends considerably beyond the support given by the parts through which it passes. Further it is extremely difficult to keep a bolt absolutely tight unless some spring be provided between the bolt or its setting-up means and the parts through which it passes, such for example, as the spring lock washers used with ordinary railways' bolts, which, however, are not adapted for use with key bolts. My object therefore is to devise means for reducing the transverse pressure on the bolt end during the driving of the key to a minimum, to provide the desired resilience in the setting up means for the bolt, and to attain these results at a minimum cost.

I attain my object by means of the constructions hereinafter described and illustrated in the accompanying drawings in which—

Fig. 1 is a side elevation of a bolt with the taper key and gib in position;

Fig. 2 a side elevation of the bolt from a position at right angles to Fig. 1; and

Fig. 3 a cross section of the gib.

In the drawings like numerals of reference indicate corresponding parts in the different figures.

1 is a key bolt, which in essentials is the same as the keybolt shown and described in United States Patent No. 1,266,334 dated May 14th, 1918. 2 is the slot therein for the passage of the key. 3 is the taper key. Heretofore it has been usual to drive this key between the end 4 of the slot and the parts which the bolt is employed to connect. In the improved construction the bolt and slot are so proportioned that space is

provided adjacent the end 4 of the slot for a gib 5, the key 3 being driven between the gib and the parts which the bolt is used to connect. This gib is formed with shoulders 6 which engage the sides of the bolt and prevent longitudinal movement of the gib when the taper key is in position. The inner edge of the gib is preferably given a smooth finish and is tapered to correspond with the taper of the key 3. The contacting edges of the taper key and gib are preferably given a smooth finish so as to reduce the lateral pressure tending to bend the bolt end as much as possible. I find that by employing a gib as described that the key can be driven tightly without springing or bending the bolt end.

To give the desired resiliency referred to in the preamble of this specification, the inner face of the gib is concaved or arched as shown, so that the gib contacts with the back of the taper key only at its ends, these contacting surfaces being spaced from the sides of the bolt so that the gib forms in effect an arch loaded at the center and supported at each end.

A certain amount of friction is desirable to tend to prevent the taper key backing up, while it is desirable also that it should be possible to fit the gib in position with as little trouble as possible. I therefore so proportion the slot, the gib and the taper key that the gib will fit loosely in the slot, while there is a tight fit between the sides of the taper key and the sides of the slot. This is best effected by making the tapered key and the gib of the same gauge material, while the outer part of the slot is slightly increased in width, as shown particularly in Fig. 2. The gib is thus easily slipped into place. When the taper key is driven there is friction between the sides of the slot and the sides of the key, between the inner edge of the key and the part through which the bolt passes, and further frictional resistance between the ends of the gib and the outer edge of the key. This friction is sufficient under all ordinary conditions to prevent the key backing out, while it is always possible to deform the end of the key after it has been driven to give added security.

It is also desirable to so apply the pressure of the back of the gib to the end of the bolt that this pressure tends to contract the sides of the slot of the bolt rather than otherwise. I therefore round the back of the gib trans-

versely so that the pressure is concentrated as nearly as possible along the line of intersection of the median plane of the slot with the end of the bolt, or at least so that the 5 pressure is not concentrated on the parts of the end adjacent the sides of the slot. By thus rounding the back of the gib I find that a tendency exists to contract the sides of the slot and this increases the friction of the 10 sides of the slot against the sides of the taper key.

It should be noted that frictional contact 15 between the sides of the taper key and the sides of the slot is not objectionable in any way, as any transverse pressure tending to bend the bolt end is exerted close to the part through which the bolt passes, and consequently resistance to bending is at a maximum.

20 What I claim as my invention is:—

1. A slotted bolt in combination with a taper key and a gib adapted to fit in the slot, the gib being shouldered at the back for engagement with the end of the bolt at 25 opposite sides thereof and having its front edge tapered and concaved so that its surfaces of contact with the key are spaced from the sides of the bolt, the gib thus forming in effect an arch loaded at the center and supported at each end.

2. A slotted bolt in combination with a taper key and a gib adapted to fit in the slot, the gib being shouldered at the back for engagement with the end of the bolt at 35 opposite sides thereof, the back of the gib between the shoulders being transversely rounded and the front edge of the gib tapered and concaved so that its surfaces of contact with the key are spaced from the sides of the bolt, the gib thus forming in effect an arch loaded at the center and supported at each end.

3. A slotted bolt in combination with a

gib loosely fitting between the sides of the slot adjacent its outer end and a taper key 45 fitting tightly between the sides of the slot remote from the outer end, the gib being shouldered at the back for engagement with the end of the bolt at opposite sides thereof and having its front edge tapered and concaved so that its surfaces of contact with the key are spaced from the sides of the bolt, the gib thus forming in effect an arch loaded at the center and supported at each end.

4. A slotted bolt in combination with a 55 gib loosely fitting between the sides of the slot adjacent its outer end and a taper key fitting tightly between the sides of the slot remote from the outer end, the gib being shouldered at the back for engagement with the end of the bolt at opposite sides thereof, the back of the gib between the shoulders being transversely rounded and the front edge of the gib tapered and concaved so that its surfaces of contact with the key are 65 spaced from the sides of the bolt, the gib thus forming in effect an arch loaded at the center and supported at each end.

5. A slotted bolt in combination with a taper key and a gib adapted to fit in the slot, 70 the gib being shouldered at the back for engagement with the end of the bolt at opposite sides thereof, the back of the gib between the shoulders being transversely rounded and the front edge of the gib tapered. 75

6. A slotted bolt in combination with a gib loosely fitting between the sides of the slot adjacent its outer end and a taper key fitting tightly between the sides of the slot remote 80 from the outer end, the gib being shouldered at the back for engagement with the end of the bolt at opposite sides thereof and having its front edge tapered.

Signed at Toronto, Canada, this 25th day of November, 1921.

JOHN PELL NORTHEY.
